UNITED STATES PATENT OFFICE

FOLKE J. GUSTAFSON AND HOLGER C. GUSTAFSON, OF CHICAGO, ILLINOIS

CHRISTMAS TREE SUPPORT

Application filed December 2, 1931. Serial No. 578,504.

This invention relates to an improvement in Christmas tree supports and has for one of its principal objects the provision of means whereby a Christmas tree is conveniently maintained in an upright position.

One important object of this invention is to provide a Christmas tree support which includes as an integral part thereof means for maintaining a body of water about the base 10 of the tree to retain the same moist and green as long as possible.

Another important object of the invention is to provide spurs integral with the legs of the support and at the upper end thereof 15 which spurs securely grip the tree trunk regardless of size.

A further important object of the invention is the provision of a cone-shaped combination water container and tree trunk support which is itself suspended between and forms a support for the supporting legs of the holder itself.

Another and still further important object of the invention resides in the provision of a 20 novel and convenient means of pivotally mounting the supporting legs on the central bracket and water container.

Other and further important objects of the invention will be apparent from the disclosures in the accompanying drawing and following specification.

The invention, in a preferred form, is shown in the drawing and hereinafter more fully described.

35 In the drawing:

Figure 1 is a side elevation of the Christmas tree holder of this invention, showing generally the supporting legs and the conical container.

40 Figure 2 is a detail view of one portion of the upper edge of the container, showing the improved method for pivotally mounting the supporting leg thereon.

Figure 3 is a top plan view of the structure shown in Figure 2.

Figure 4 shows a slight modification of the mounting illustrated in Figures 2 and 3.

Figure 5 is a detail view illustrating the spur on the upper end of the supporting leg 50 and showing the same as penetrating the tree

trunk. A portion of the trunk is broken away.

Figure 6 is a detail view showing a slight modification of the mounting illustrated in 55 Figure 4.

As shown in the drawing:

The reference numerals 10 indicate generally the supporting legs or braces, the lower ends of the same being curved as shown to present a relatively large surface to a supporting floor or the like which at the same time is readily slidable so as to insure a proper gripping of the tree trunk at the upper ends of the braces and without any possibility of marring the floor or other supporting surface. A cone-shaped container 12 preferably of metal is provided for supporting the base of the tree and also is made liquid-tight so that water may be poured thereon for the purpose of retaining the tree in a fresh and 60 green condition for a considerable length of time. The upper edges of the container 12 are rolled over a rod or wire 14, thereby providing a reinforced rigid edge which rod at 65 the same time is used as a mounting for the 70 legs or brackets 10.

A preferred embodiment of the mounting of a leg 10 on the rod 14 is illustrated in Figures 2 and 3, this providing a removable 75 pivotal attachment, and as illustrated in 80 these figures, a portion of the rod is brought out of a cut-away part of the rolled-over edge of the container 12 and is first bent outwardly, thence slightly upwardly as shown at 16, then reversely curved as illustrated at 85 18, providing an eye 20, after which the rod is bent back to contact with itself as shown in Figure 2. The rod is then bent into a U-shape as best shown at 22 in Figure 2. Bends

similar to the original bends 16 and 18 are 90 made providing another eye parallel to the first eye and slightly spaced therefrom as shown in Figure 3 which allows of the insertion therebetween of the corresponding 95 central portion of the supporting leg or brace 10. A suitable opening is provided in the supporting brace through which passes a bolt 24 having a removable nut 26 on one end thereof whereby the same can be readily removed and the leg dismounted for packing 100

into a small compass whereby convenient packing and transportation is rendered feasible.

At the upper end of each brace a portion 5 is cut away as illustrated at 28 in Figure 5, thereby providing a sharp point or spur 30 which is adapted to penetrate the material of the tree trunk 32 for a distance sufficient to afford a substantial grip whereupon the 10 tree is positively maintained in desired position at this point.

The weight of the tree itself when the lower end of the trunk is positioned in the 15 container 12 will center the same in the container, and the resultant spreading action of the legs 10 will serve to automatically center that portion of the trunk where the spurs penetrate, at the same time affording a base of sufficient dimensions.

20 No manual adjustment whatever is necessary, the simple positioning of the tree in the device accomplishing the desired result. In this manner, a rigid suspension of the trunk itself results with no liability of shaking, 25 wabbling, and consequent possible overturning.

In the event that a simpler mounting between the bracket 10 and the upper edge of the conical container 12 is desired, the rod 30 34 can be simply passed through the rolled-over upper edge of the container 12 and threaded through the opening in the bracket 10, this bracket being inserted into a slot 36 cut into the upper edge of the container 12 35 for its reception. In this way, a suitable pivotal mounting results which, however, has not the advantage of being removable.

However, as illustrated in Figure 6, a removable mounting for this embodiment of 40 the invention may be provided by incorporating a bayonet slot 38 into a leg or bracket 40 which bayonet slot will suitably receive and retain the corresponding portion of the rod 34 and without any possibility of the same becoming loose or shaking to an undesirable 45 degree.

It will be evident that herein is provided a Christmas tree holder which embodies a compact, efficient, and suitable device of this 50 sort in a minimum number of parts, and one which may be conveniently and economically constructed and operated. Furthermore, the tree itself can be kept green and fresh by suitable application of water to the combined 55 support and liquid container which also provides a means for pivotally mounting the supporting legs.

The apparatus can be readily disassembled 60 for packing or shipping purposes, the construction thereby resulting in the bringing of the parts together in a small compass while at the same time, they can be readily reassembled by anyone without any special tools or the like.

65 We are aware that many changes may be

made and numerous details of construction varied throughout a wide range without departing from the principles of this invention, and we, therefore, do not purpose limiting the patent granted herein otherwise than as 70 necessitated by the prior art.

We claim as our invention:

1. A Christmas tree holder, including a receptacle for the bottom of the tree trunk, and a plurality of supporting legs pivotally 75 mounted on the receptacle, and a reinforcing bar in the upper rim of the receptacle, said reinforcing bar comprising a pivotal mounting for the supporting legs, a portion of the upper edge of the receptacle being cut away 80 to allow of a connection between the leg and the bar, the bar being bent outwardly at said cut-away portion, thence looped to form an eye, and reversely upon itself, and again looped to form a parallel eye, and finally continuing into the said rolled-over edge of the receptacle.

2. A Christmas tree holder, including a receptacle for the bottom of the tree trunk, and a plurality of supporting legs pivotally 90 mounted on the receptacle, and a reinforcing bar in the upper rim of the receptacle, said reinforcing bar comprising a pivotal mounting for the supporting legs, a portion of the upper edge of the receptacle being cut away to allow 95 of a connection between the leg and the bar, the bar being bent outwardly at said cut-away portion, thence looped to form an eye, and reversely upon itself, and again looped to form a parallel eye, and finally continuing into the said rolled-over edge of the receptacle, and a removable bolt passing through the eye, and a corresponding opening in the leg.

In testimony whereof we affix our signatures.

FOLKE J. GUSTAFSON.
